QUILL TENSIONING MEANS

Stanley Johnson, Chicago, Ill., assignor to Borg-Warner Corporation, Chicago, Ill., a corporation of Illinois

Application November 7, 1938, Serial No. 239,232

8 Claims. (Cl. 140—3)

This invention relates to a tensioning device for a quill arranged to feed the warp wire in a wire fabric weaving machine and has particular application to the rotating quill of a weaving machine arranged to produce an integrating twist 5 of the pairs of warp wires between successive ones of the transverse filler wires, an example being the type claimed in the copending application Serial No. 239,240 of one Walkley B. Ewing and the co-pending application Serial No. 239,257 of one Heinz, both filed simultaneously herewith.

In a weaving machine of the above type where-in the quill functions both to feed the warp wire and to move the same relative to the median plane 15 of the cloth for the purpose of forming the requisite shed, the resistance to the passage of the warp wire along the quill must be controlled to a relatively fine degree if a satisfactory operation is to be accomplished. This is particularly true where the quill must produce an interlocking twist between pairs of warp wires since these ties must be made of consistent firmness if the cloth is to be symmetrical in appearance and if it is to satisfy the rigid specifications required 25 of this type of cloth.

It is an object of the present invention to provide an arrangement for applying a predetermined refined degree of resistance to the passage of warp wire along a quill which supplies warp 30 wire to the weaving mechanism of a wire fabric weaving machine.

It is a further object to provide an arrangement for applying a predetermined refined degree of resistance to the passage of a pair of substantially 35 diametrically opposed warp wires along the respective quills of a row of rotatable quills that supply warp wire to the weaving mechanism of a wire fabric weaving machine.

It is a still further object to provide a novel 40 arrangement for applying a refined degree of resistance to the passage of pairs of warp wire along the respective rotatable quills of a weaving machine wherein said quills serve both to feed the warp wire and to produce firm integrating twists 45 between successive laterally injected filler wires of elongated cross-section positioned in the fabric with the major surfaces thereof disposed at an angle to the plane of the fabric.

A more particular object is the provision in 50 combination with the above of means for applying a predetermined pull-away force to the fabric as the same is drawn from the weaving machine.

The more specific objects and results of my invention will be made apparent from a reading of 55 the following detailed specification taken together

with the appended drawing forming a part thereof and wherein:

Fig. 1 is a broken away vertical section of the essential parts of a weaving head assembly incorporating my novel tensioning device; 5

Fig. 2 is a broken away plan view corresponding to Fig. 1; and

Fig. 3 is an end elevation in section taken substantially on line 3—3 of Fig. 1 and showing to advantage the novel manner in which the tensioning 10 means cooperates with the warp wire and guide therefor formed in the quill.

The essential parts of one form of weaving machine with which my novel tensioning device is particularly adapted to cooperate is shown 15 as composed of a comb assembly indicated generally at 10 guidably receiving and holding flat filler wire 11 with the major surface thereof at an angle to the plane of the fabric, while pairs of warp wires 12 are embracingly fed thereabout and 20 twisted to define interlocking twists 13 between successive filler wires 11 by means of rotatable quills 14 cooperating with the comb assembly. The comb assembly 10 includes a plurality of teeth 15 vertically reciprocable on the forward 25 face of a backplate 16 from a position wherein the teeth 15 extend between adjacent pairs of warp wires and separate a previously tied in filler wire 11 from a subsequently injected filler wire 11 to be tied in by the rotation of the quills 14 of 30 which there are a plurality, one corresponding to each pair of warp wires. The backplate 16 is formed with a plurality of vertical slots 17 corresponding in position to the spaces between the teeth 15 for the passage of the warp wires there- 35 through. The vertical slots 17 in the backplate 16 are diverged to form vertical channels 18 for the reception of the wedge-shaped noses 19 of the quills 14 to a position closely adjacent but not touching the rear portion of the backplate. 40

The quills 14 are provided with gear teeth 21 arranged to be driven at successive intervals by the teeth 22 of a rack 23 for effecting the rotation thereof to produce the interlocking twist 13.

Suitable means are provided for raising and lowering the comb teeth 15 on the forward face of the backplate 16 and for shifting both the comb teeth and the backplate forward and backward in carrying out the weaving operation as well as additional means for operating rack 23, however, 50 for purpose of simplicity, this mechanism is not shown since it is not deemed necessary to the complete disclosure of the present invention and further since the same is amply disclosed and claimed in the above referred to applications. 55

Warp wire tensioning device

The quills 14 are formed with channel guides 25 substantially diametrically opposed to each other extending from the rear end to the forward nose thereof. Adjacent the rear end of the quill, the portion 26 of the guide 25 is reduced in depth to less than the diameter of the round warp wire 12. A coil 27 of spring steel wire is embracingly received about the rear end portion of the quill 14 in contact with the warp wires 12 above the shallow portion 26 of the guide 25. The coil 27 is made of such strength that the same contracts about the warp wires 12 to produce the desired refinement of resistance to the passage of wires 12 along the quills 14. This pressure is capable of being predetermined to a very high degree of refinement by varying the normal contracted diameter of the coil employed; by varying the strength of the wire employed; as well as by varying the number of turns forming the coil. In view of the fact that the coil 27 surrounds the end of the quill, there is no danger of the tension being varied by the tensioning means slipping and changing its relation to the warp wires 12. Any movement that does take place will be in the direction of the enlarged portion of the quill and this will have no effect upon the tension.

I have found that my tensioning device works to particular advantage when employed in connection with the additional provision of adjustable weight 29 for applying a predetermined pull-away force to the fabric as it leaves the weaving head and is wound up upon reel 29a. Other means such for example as a torque motor may be employed to equal advantage for this purpose.

While the machine disclosed in the above referred to copending applications is new, I have found that a tension of one pound in each of the coil springs 27 and a constant pull-away force of seventy pounds applied to the cloth as it comes off of the machine produces the most satisfactory results. It is apparent of course that these values may require change during the life of the machine. The tension exerted by the coil 27 may be readily reduced by cutting off a portion thereof or other springs having the requisite characteristics may be substituted therefor.

In the operation of weaving, assuming the parts to be positioned as shown in the drawing, a flat filler wire 11 having been injected into the guideway defined by the channel in the back-plate 16 and the comb teeth 15, the first step is the shifting forward of the comb assembly a small distance indicated by the arrow 30 in order to permit of the rotation of the noses 19 of quills 14 in channel 18. Next the quills 14 are rotated 360° by means of rack 23 to produce an interlocking twist 13 on the backside of filler wire 11, thereby tying the same in place in the fabric. Following this integrating tie operation, the comb assembly is shifted forward a still further distance indicated by the arrow 31 for the purpose of advancing the fabric and at the same time, comb teeth 15 are lowered as indicated by arrow 32 and next the assembly is shifted backward to the original position and the comb teeth 15 again raised to a position behind the tied in filler wire preparatory to the injection of a subsequent filler wire 11 likewise to be tied in by a repetition of the above described sequence of operation. It is important to note that the for-

ward movement of the comb assembly indicated by the arrow 31 is effective to draw the shed-forming portions 12a of the warp wires 12 away from the nose of the quills without appreciably deforming or straightening the elbow portion 12b thereof. This is one of the important results flowing from my novel arrangement of tensioning means. The result of this operation is to provide a sufficient size and shape of shed to permit of the introduction of the elongated filler wires 11 with the major surfaces thereof disposed at an angle to the plane of the fabric, while at the same time the refined resistance to the passage of warp wires 12 along the quill 14 is such that when the quill 14 is rotated, a firm and consistent interlocking twist 13 is effected. This operation is further improved by the functioning of the constant pull-away mechanism including the adjustable weight 29.

While I have disclosed one specific embodiment of my invention by way of example, it is to be understood that other forms may be provided coming within the scope of my invention and I do not desire to be limited further than as indicated by the appended claims, which should be construed as broadly as the prior art will permit.

By way of example of other equivalent forms contemplated by my invention, I may employ a spring steel band in place of the spring steel wire shown in the drawing.

I claim:

1. In a metal fabric weaving machine wherein a quill is employed to feed a warp strand, the improvement which comprises said quill being formed with a generally coaxially extending guideway therein for said warp strand, and resilient means carried by said quill effective to place said warp strand under a predetermined tension, said resilient means comprising a coiled spring steel member embracing said quill in contact with said warp strand and urging the same against said guideway with a predetermined pressure.

2. In a wire fabric weaving machine wherein a quill is employed to feed a warp strand, the improvement which comprises said quill being formed with a substantially coaxially extending guideway therein for said warp strand, said guideway being sufficiently shallow so as not to completely receive said warp wire therein, and resilient means carried by said quill effective to place said warp strand under a predetermined tension, said resilient means comprising a coiled spring steel member of at least one turn embracing said quill in contact with said warp strand and urging the same against said guideway with a predetermined pressure.

3. In a metal fabric weaving machine wherein quills are employed to feed warp strands, the improvement which comprises said quills being formed with guideways therein for said warp strands, resilient means carried by said quills in contact with said warp wires effective to urge the same against said guides for placing the same under a predetermined tension, said resilient means comprising a coil of spring steel wire embracing said quill.

4. In a metal fabric weaving machine wherein quills are employed to feed warp strands, the improvement which comprises said quills being formed with guideways therein for said warp wires, said guideways being sufficiently shallow so as not to completely receive said warp wires therein, and resilient means carried by said quill

in contact with said warp wire effective to urge the same against said guideways for placing the same under a predetermined tension, said resilient means comprising a coil of several turns 5 of resilient steel wire embracingly received about said quill in contact with said warp wire.

5. In a wire fabric weaving machine wherein quills are employed to feed a pair of warp wires about a filler wire and rotatable to produce an interlocking twist between the wires of said pair for locking said filler wire into place, said quills being formed with a pair of substantially diametrically opposed coaxial guideways along said quill for said warp wires and means for applying 10 a predetermined resistance to the passage of said warp wires along said guideways, said means comprising forming a portion of each of said guides of a depth less than the diameter of said warp wires, a coil of a predetermined number of 15 turns of spring steel wire embracing said quills in contact with said warp wires in the area of said shallow portions of said guides whereby the contraction of said coil of wire is effective to force said warp wires against said shallow guides with 20 a predetermined pressure resulting in the production of a firm interlocking twist between said pairs of warp wires when said quill is rotated but permitting of the drawing of said warp wires along said guides when said cloth is advanced 25 through said weaving head, and means for applying a predetermined pull-away force to said fabric for facilitating the movement thereof away from said weaving head.

6. In a wire fabric weaving machine wherein 30 a row of rotatable quills is employed to feed a plurality of pairs of warp wires about a filler wire of elongated cross-section positioned with the major surfaces thereof at an angle to the plane of the fabric and wherein said quills are 35 rotatable to produce an interlocking twist between the respective wires of each pair of warp wires for locking said filler wire into place and for defining a shed for the subsequent injection of an additional filler wire, said quills being 40 formed with a pair of substantially diametrically opposed coaxial guideways for said warp wires and discharging said warp wires from the forward ends of said guideways at diametrically opposed points on the forward ends of said quills 45 to a preceding tie to thereby define said shed and means for applying a predetermined resistance to the passage of said warp wires along said guideways, said means comprising forming a portion of each of said guides of a depth less than 50 the diameter of said warp wires, a coil of a predetermined number of turns of spring steel wire embracing said quills in contact with said warp wires in the area of said shallow portions of 55 guides whereby the contraction of said coil of wire is effective to force said warp wires against said shallow guides with predetermined pressure resulting in the production of a firm interlocking twist between said pairs of warp wires when said quill is rotated by permitting of the drawing 60 of said warp wires from said guides in response to the forward movement of the cloth without appreciably changing the shape of the shed defining portion of said warp wires prior to the rotation of the quill, and means for applying a predetermined pull-away force to said fabric for facilitating the movement thereof away from said 65 weaving machine.

7. In a weaving machine for weaving wire fabric composed of a plurality of pairs of longitudinally extending warp wires and a plurality of transversely extending filler wires of elongated cross-section having their major surfaces disposed at an angle to the plane of the fabric, said pairs of warp wires being twisted together between successive ones of said filler wires whereby to produce an interlocking relation for firmly tying said filler wire into said fabric, a comb assembly for guidably receiving and holding said filler wires, a row of rotatable quills formed with substantially diametrically opposed coaxial guideways for feeding said pairs of warp wires about said filler wires and rotatable to produce said interlocking twists, the combination therewith of means for enlarging the size of the shed into which said filler wire is introduced, said means comprising forming a portion of each of said guideways on said quills of a depth less than the diameter of said filler wire, a coil of spring steel wire embracingly received about said quill in the area of said shallow guide portions in contact with said warp wires for producing a predetermined refined resistance to the passage of said warp wires along said guideways, and means for applying a predetermined pull-away force to said fabric as the same is drawn away from said comb assembly, said arrangement of tensioning means resulting in a firm consistent tie when said quills are rotated by permitting of the movement of said warp wires from the noses of the quills without appreciably distorting the shape of the shed defining portion when the cloth is advanced preparatory to the introduction of an additional filler wire.

8. In a wire fabric weaving machine wherein a rotatable quill is arranged to cooperate with a comb assembly for feeding pairs of warp wires about a filler wire of elongated cross-section held at an angle to the plane of the fabric and wherein said warp wires pass off of the forward nose of said quill at diametrically opposed points and extend to an interlocking twist thus defining a shed composed of a pair of elbow-like portions adjacent the points of discharge connected by shed portions to said interlocking twist, said arrangement being particularly characterized by the formation of said guide portions of a depth less than the diameter of said warp wires, a coil of spring steel wire embraceably received about said quill in the area of said shallow portions in contact with said warp wires producing a refined degree of resistance to the passage of said warp wires from the forward end of said quill, means for applying a predetermined pull-away force to said fabric as it is drawn away from said machine, said comb assembly adapted to be advanced to control the forward movement of the fabric subsequent to the rotation of said quill to produce interlocking twist between said warp wires, said arrangement of tensioning means resulting in a firm consistent tie when said rotation of said quill takes place, however permitting the withdrawal of the warp wires from the forward nose of said quill when said comb assembly is moved forward without appreciably changing the shape of said elbow portions of said shed thus resulting in a wider shed being presented for the reception of a subsequent filler wire.
